UNITED STATES PATENT OFFICE.

ALVAN A. SIMONDS, OF DAYTON, OHIO.

PAPER-DRYING MACHINE.

SPECIFICATION forming part of Letters Patent No. 366,893, dated July 19, 1887.

Application filed November 2, 1886. Serial No. 217,840. (No model.)

To all whom it may concern:

Be it known that I, ALVAN A. SIMONDS, a citizen of the United States, residing at Dayton, in the county of Montgomery and State 5 of Ohio, have invented certain new and useful Improvements in Paper-Drying Machines; and I do hereby declare the following to be a full, clear, and exact description of the invention, such as will enable others skilled in the art 10 to which it appertains to make and use the same.

My invention relates to the class of paper-driers in which the paper is passed through a narrow box and is subjected to the action of a highly-heated blast of air therein. Where 15 the air for drying is admitted at both top and bottom of the box, and where the paper web acted upon is of considerable strength and thickness, no support for the paper is required within the box, as the current of air supplied beneath the web will be sufficient to prevent it from dragging or clogging; but it may sometimes be desired to dry a very thin web of paper, in which case the current or currents of 20 air will be of less force, and the paper web being thin and of less strength, it is desirable in such case to afford some support for the paper web and at the same time permit the current of air to be in contact with said paper web 25 and not be diverted therefrom. It is also desirable in the drying of all classes of paper, and especially the lighter and thin articles of that class, to have means whereby the operator may have access to the interior of the 30 tube for the introduction of the paper web and to assist in the passage through the box where the web is broken or torn.

The object of my present invention is to provide a construction which will give ready 40 access to the interior of the tube and will furnish a satisfactory support for a thin web of paper within the same. One form of construction for accomplishing these results is shown in the accompanying drawings, and described in this specification, and the invention 45 is fully pointed out in the claims.

In the drawings, Figure 1 is a view of a portion of a drier constructed in accordance with my invention, the drying tube or box and 50 the parts connected therewith being shown in section. Fig. 2 is a plan view of the same with a portion of the top broken away to

show an interior construction. Fig. 3 shows the shaft employed in one form of my interior support.

In the drawings, A designates the drying tube or box. B are the supporting-rolls for the paper web at either end of the same. C C are the air-inlets near one end of the tube or box A. The top of the box or tube is provided with two doors or movable covers, a, one at each side of the box, extending nearly the entire length of the same. In the drawings these doors are shown as hinged at a' a' to a central portion of the top of the tube; but it is obvious that these doors or movable covers may constitute the entire top of the tube or box, and they may be hinged to open outwardly instead of in the manner shown, though such construction is not thought to possess the advantages of a cover opening toward the center. It is also apparent that these doors or movable covers might be made to slide instead of being hinged, and that they might be made to consist of a number of parts, each independently movable, and that such doors or covers might be made to slide under a central piece, substantially as shown in the drawings.

In order to give access to the end of the tube at which the air-inlets are placed, the air-tube and its directing-chute are attached to a portion of the top c and the air-tube provided with a swivel-joint, such as shown at c'. Instead of the swivel-joint being located in a portion of the pipe parallel to the pipe discharging into the drier, it might be in the portion c', which is at right angles thereto. The part c of the top is not connected to any other portion of the top or with the box; but being attached to the pipe C by turning the pipe C upon its swivel at c', the top c is lifted and turned away from the end of the box, giving the operator full access thereto.

In Fig. 1 I have shown in section two different constructions for supporting a thin web of paper and directing the air against the same. One of the constructions consists of a small roller, D, journaled in the side of the box or tube. This roller is of less diameter than the distance from the path of the paper web to the lower side of the box. This admits of a passage of air beneath the same; but as the air in such case would be directed away from

the paper, I place a guide, d , inclining from the bottom upward toward the paper to direct the air against the same. In the other construction shown I employ a shaft, D' , which is provided at intervals with narrow fixed collars D^2 . The diameter of these collars is equal to the distance from the path of the paper web to the lower side of the box, and, the paper web coming in contact with the upper part of these collars, is supported in its proper position. In order that the air admitted to the tube beneath the paper web may be directed against it, I place over the shaft D' a guide, d' , consisting of a sheet of rigid material provided with slots or openings through which the collars D may project. The portion of this guide between the slots is supported just above the shaft D' , and its edges are bent downward and attached to the bottom of the tube or box A. Instead of making D' of a sheet of thin material, it may be made of a solid material with openings for the shaft D' and recesses for the collars D^2 .

The operation of the construction shown and described it is thought will be clearly understood from the foregoing description. In introducing the thin web of paper the pipe C is turned, giving the operator access to the interior of the drier at that end. The web being introduced through the narrow slot, the operator returns the pipe C to its place, and, opening one of the doors a , carries the web through the box to the rolls on the other side. The web, coming in contact with the collars D^2 of shaft D' , is supported in proper position during its traverse through the box or drier, while the air admitted to the under side of the paper web will have a sufficient space to pass beneath the paper and will be directed against the same. It will be noticed that the guide d' , when made of sheet material, is made to extend to both sides of the shaft D' merely for convenience and to give it rigidity. Such guide might be divided in the center along the line of the shaft and the part farthest from the air-inlets dispensed with, the inclined portion rising from the bottom of the box to the top of the shaft between the shaft and the air-inlets being the only part necessary to effect the result desired.

It will be noticed that in the description of the operation herein the paper web is spoken of as moving from the end provided

with a narrow slot toward the other end. I do not desire to limit myself to such a movement of the paper, but the paper, if desired, may be passed through the drier in a reversed direction.

I have shown and described a drier consisting of a narrow box or tube having air-inlets at the top and bottom at one end and an opening the full size of the tube at the other end; but this construction is not claimed herein, as it forms the subject-matter of my application, No. 202,119, now pending.

What I claim, and desire to secure by Letters Patent, is—

1. The combination, with a box or tube having an opening at each end for the passage of the paper web therethrough, of an air-inlet in the top near one end of said box, and doors or movable covers extending along both edges of said box, a portion of the cover being connected with the air-inlet and said air-inlet being provided with a swivel, substantially as described.

2. The combination, with a narrow tube or box having openings at each end for the passage of a paper web therethrough and air-inlets at top and bottom near one end, of a support for the paper web, consisting of a roller having a space beneath the same and a guide inclining from the bottom of the tube upward toward the paper, substantially as described.

3. The combination, with the tube or box having openings at each end for the passage of a paper web therethrough, air-inlets at top and bottom near one end of said box, a supporting-roll for the paper web, consisting of a shaft provided with rigid collars and an air-guide on the side nearest the air-inlets inclining from the bottom of the box to the top of the shaft between the collars, substantially as described.

4. The combination, with the tube or box having openings at each end for the passage of a paper web therethrough, of a support for the web within the box, consisting of shaft D' , provided with collars D^2 , and the slotted guide d' , substantially as described.

In testimony whereof I affix my signature in presence of two witnesses.

ALVAN A. SIMONDS.
